Patented Mar. 14, 1916.

Inventor

JAMES D. BUSH

By Watson E. Coleman

Attorney

UNITED STATES PATENT OFFICE.

JAMES DENNISTON BUSH, OF MOBILE, ALABAMA.

BEATER.

1,175,598.

Specification of Letters Patent. Patented Mar. 14, 1916.

Application filed December 4, 1915. Serial No. 65,116.

To all whom it may concern:

Be it known that I, JAMES D. BUSH, a subject of the King of Great Britain, residing at Mobile, in the county of Mobile and State of Alabama, have invented certain new and useful Improvements in Beaters, of which the following is a specification, reference being had to the accompanying drawings.

10 This invention relates to certain improvements in beaters and has relation more particularly to a device of this general character especially designed for use for the whipping of eggs or cream and it is an object of 15 the invention to provide a device of this general character having novel and improved means whereby it may be applied into operative position with convenience and facility and whereby it may be operated 20 with a maximum of efficiency.

Furthermore, it is an object of the invention to provide a beater of this general character having novel and improved means wherein a rotatable sleeve is employed and 25 mounted for rotary movement upon a rod, said rod and sleeve being provided with co-acting means whereby the requisite rotation may be imparted to the sleeve.

The invention consists in the details of 30 construction and in the combination and arrangement of the several parts of my improved beater whereby certain important advantages are attained and the device is rendered simpler, less expensive and otherwise 35 more convenient and advantageous for use, all as will be hereinafter more fully set forth.

The novel features of the invention will be carefully defined in the appended claim.

40 In order that my invention may be the better understood, I will now proceed to describe the same with reference to the accompanying drawings, wherein—

Figure 1 is a view partly in section and 45 partly in elevation illustrating a beater constructed in accordance with an embodiment of my invention and in applied position; Fig. 2 is a view in elevation detached of the operating disk herein embodied; Fig. 3 is a 50 view in top plan detached of the sleeve or tubular member as herein embodied; and Fig. 4 is a sectional view taken substantially on the line 4—4 of Fig. 1.

As disclosed in the accompanying drawings, C denotes a container preferably of the well known type of Mason jar and with

which the top T is adapted to be detachably engaged in a conventional manner. At its axial center the top T is provided with an opening 1 through which is disposed the 50 tubular member or sleeve 2 of predetermined dimensions, the upper end portion of said sleeve or tubular member being enlarged to afford the annular shoulder 3 adapted to engage the upper or outer surface of the 55 top T. The upper or outer end portion of the sleeve or tubular member 2 has formed therein the teeth 4 for a purpose to be hereinafter more particularly referred to.

5 denotes a rod adapted to be disposed 70 through the tubular member or sleeve 2 and to extend beyond the opposite ends thereof, the lower end of said rod preferably contacting with the base of the container C at its axial center and the upper end of said 75 rod is enlarged transversely to afford the shoulder 6 adapted to engage the upper or outer end of the tubular member or sleeve 2 in order to maintain the rod 5 and the tubular member or sleeve 2 in assembled relation. It is also preferred that the enlarged portion 16 of the rod 5 be angular in cross section and one of the faces of said enlarged portion 16 is provided with a stub shaft 7 on which is rotatably mounted the disk 8 85 having its inner face provided with a circular series of teeth 9 adapted to engage the teeth 4 of the tubular member or sleeve 2 whereby it will be perceived that upon axial rotation being imparted to the disk 8, the 90 sleeve or tubular member 2 will be caused to rotate in unison therewith. While any means may be employed for imparting axial rotation to the disk 8, I prefer to employ, as illustrated in the accompanying drawings, the hand grasp 10 of ordinary construction. I also find it of advantage to provide the sleeve 2 at a predetermined point below or inwardly of the top T with the annular flange 11 preferably of leather 100 which serves to limit the upward movement of the sleeve or tubular member 2 relatively to the top T or container C. I also find it of advantage to have detachably engaged with the lower extremity of the rod 5, the 105 button or member 12 also preferably of leather whereby it will be perceived that relative independent endwise movement of the tubular member or sleeve 2 and the rod 5 is prevented but whereby said rod 5 and 110 sleeve or tubular member 2 may be separated when desired, upon removal of the button or

member 12. Secured to the lower end of the sleeve or tubular member 2 are the circular series of blades 14 arranged in predetermined spaced relation longitudinally of the sleeve with the blades of one series alternately arranged relative to the blades of a second series and, as herein embodied, each of the blades is of substantially L-shape form with the stem thereof suitably anchored as at 15 to the sleeve or tubular member 2 with the stem of the blade extending radially from the tubular member or sleeve 2. It will be readily understood that upon rotation of the sleeve or tubular member 2, the blades 14 will serve to effectively whip the eggs or cream deposited within the container C.

From the foregoing description, it is thought to be obvious that a beater constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

Copies of this patent may be obtained for five cents each, by addressing the "Commissioner of Patents, Washington, D. C."

What I claim is:

In combination with a container and its top, a sleeve disposed through the top and capable of rotation, said sleeve being provided with an annular shoulder engageable with the outer face of the top to limit the passage of the sleeve through the top, an annular flange carried by the sleeve inwardly of the top engageable with the under face of the top for limiting the movement of the sleeve in an opposite direction, a rod disposed through the sleeve, the outer end portion of the rod being enlarged and affording a shoulder coacting with the outer end of the sleeve, an annular series of teeth formed in the outer end of the sleeve concentric to the axis thereof, a disk rotatably supported by the enlarged portion of the rod and provided with teeth meshing with the teeth of the sleeve, said disk being provided with operating means, blades carried by the inner extremity of the sleeve, a member engaged with the inner extremity of the rod and coacting with the inner end of the sleeve for holding the sleeve and rod in operative assemblage.

In testimony whereof I hereunto affix my signature in the presence of two witnesses.

JAMES DENNISTON BUSH.
